Patented July 18, 1922.

UNITED STATES PATENT OFFICE.

ARTHUR G. GRANT AND JOHN J. FANNING, OF YARDLEY, WASHINGTON; SAID FANNING ASSIGNOR TO JOHN V. GRANT, OF YARDLEY, WASHINGTON.

RAILWAY-SWITCH LOCK.

1,422,963.

Specification of Letters Patent. Patented July 18, 1922.

Application filed October 18, 1921. Serial No. 503,563.

To all whom it may concern:

Be it known that we, ARTHUR G. GRANT and JOHN J. FANNING, citizens of the United States, residing at Yardley, in the county of Spokane and State of Washington, have invented certain new and useful Improvements in Railway-Switch Locks, of which the following is a specification.

Our present invention relates to improvements in railway switch locks for use in connection with railway switches of that type including switch stands having a horizontal actuating lever fashioned with a drop-arm which falls or drops into a notch provided therefor in the locking segment of the rotary switch actuating mechanism, and forming an automatic locking mechanism for the switch.

The primary object of the invention is the provision of locking means, in combination with the pivoted drop lever, which is compactly arranged, comparatively simple in construction and operation, composed of a minimum number of parts, durable, and with an efficient and reliable mechanism for performing its required functions. By the utilization of our invention, the labor of switching traffic devolving upon the members of the train crew is rendered less difficult in their manipulation of the switch mechanism, especially in cold weather when the brakemen are wearing gloves, as the lever may be manipulated with facility, and will automatically reset itself in locked position when returned to normal condition.

In the accompanying drawings we have illustrated one complete example of the physical embodiment of our invention wherein the parts are combined and arranged according to the best mode we have thus far devised for the practical application of the principles of our invention.

Figure 1 is a view transversely of the railway, showing a well known type of switch-stand having the subject matter of the present invention embodied therein.

Figure 2 is an enlarged, detail plan view, showing the revoluble signal shaft in section, and illustrating the relation of the locking mechanism to the locking segment of the switch.

Figure 3 is a view in elevation as seen in Figure 2 when looking from the right.

Figure 4 is a sectional view on line 4—4 of Figure 5 through the lock housing, showing 55 also a portion of the spring pressed bolt-device in section.

Figure 5 is a face view of the lock, the operating or switch lever detached, and the front plate of the lock removed for convenience of illustration.

Figure 6 is a view in perspective of the switch lever, a portion of the handle being broken off.

In the preferred form of the invention as 65 illustrated in the drawings the well known form of elevated signal and switch mechanism is illustrated in Fig. 1 where the switch stand 1 is shown in its relation to the tie 2 and the revoluble, upright signal shaft 70 3 has the signals 4 thereon. The stand is provided with the usual circular disk or segment 5 at the top thereof, and a portion of the operating mechanism 6 is indicated in connection with the switch 7. 75

Above the locking segment 5 of the stand 1, is located the head 8, that is rigidly secured to and revoluble with the shaft or upright post 3 of the switch stand, and the head is provided with a horizontally disposed, lateral arm 9 projecting therefrom, and out to the periphery of the segment for pivotally supporting the switch lever 10 at point 11 in the arm. The lever is thus pivoted to swing vertically on the pivot point 11, and, 85 when in horizontal position, may be used to revolve the shaft 3 through its connection with the arm 9 and head 8. At 9' the arm is slotted to accommodate the lever, and at 12 and 13 respectively the segment has peripheral notches to receive the lever when the switch is closed and when it is open, or vice versa.

The mechanism for locking the lever with the switch in normal position is enclosed 95 within a housing 14, preferably an integral casting of the arm 9 and rising therefrom above the periphery of the locking segment. The slot 9' of the arm terminates at the opening 15 thereof, and this opening merges 100 into a vertically disposed slot 16 of the housing, the lever 10 being pivoted in the opening 15, while the tongue 17 projects angularly from the lever and is adapted to enter the slot 16, from the rear of the lock. The 105 tongue 17 is in the form of a wedge, having

a sharpened edge 18, and an opening in the tongue is designed to receive the end of the spring pressed bolt 20, the latter being adapted to pass transversely through the 5 slot 16.

The bolt, as seen in Fig. 5, is disposed transversely and horizontally in the housing, and involves in its construction a sleeve 21 in which the spring 22 is enclosed, and 10 at the rear end of the bolt an extension 23 is provided which is fixed in the housing. The spring normally urges the bolt toward the left in Fig. 5 to project its free end into the slot 16, and of course when the tongue 15 17 of the switch lever is in normal position as in Figs. 1, 2 and 3, the free end of the bolt is passed through the orifice 19 of the tongue. As the lever "drops" or swings downwardly on its pivot 11 the wedge action of the tongue, 20 as the tongue contacts with the free end of the bolt, causes the bolt to be retracted within the housing, and when the orifice reaches position of alinement with the bolt, the latter is projected therethrough, to lock the 25 lever in position. The bolt may be retracted by the use of a switch key passed through the front plate 24 as seen in Fig. 3, which actuates the cam 25 in Fig. 5, and through the cam-piece 26 on the bolt-sleeve 21 the 30 bolt is slid to the right in the latter figure to release the tongue of the lever.

Thus when a train or locomotive, and especially the former is to pass through a switch, the front brakeman uses his key to 35 retract the bolt and release the lever, then swings the latter to horizontal position and turns the switch and signal device to dotted position as indicated in Fig. 2, leaving the lever 10 in the notch 13 of the segment to 40 hold the mechanism in position. After the train has passed through the switch, the rear brakeman raises the lever from notch 13, swings the lever around horizontally to close the switch, and the lever arm is then

permitted to drop into the notch 12 of the 45 segment. As the lever drops into the notch of the segment, the tongue 17 is projected through the slot 16, retracting and resetting the bolt as described, thus automatically locking the switch in its normal position. 50

The switch key is thus used only for the purpose of unlocking the mechanism, and the lever may be manipulated with facility and convenience by both brakemen without loss of time or unusual exertion, and the 55 required functions of the locking device are performed automatically and with reliability.

Having thus fully described our invention, what we claim as new and desire to secure 60 by Letters Patent is:—

1. The combination with a switch mechanism including a notched segment and a head revoluble with the rotatable shaft, of a slotted lateral arm on the head and a switch 65 lever pivoted therein, a slotted housing on the arm and a spring pressed bolt therein, and an integral wedge shaped tongue having an orifice and projecting from said lever adapted to enter the slotted housing and 70 co-act with said bolt for locking the lever.

2. The combination in a switch lock with a notched segment, a revoluble shaft, a head thereon and a slotted arm on the head, of a drop lever pivoted in the slotted arm and 75 provided with an integral angularly disposed, wedge shaped, perforated tongue, a lock housing on the arm having a vertically arranged slot to receive said perforated head, a transversely extending spring-pressed bolt 80 in the housing adapted to enter said perforated tongue, and key actuated mechanism for retracting the bolt.

In testimony whereof we affix our signatures.

A. G. GRANT.
JOHN J. FANNING.
